UNITED STATES PATENT OFFICE

2,433,037

BOTTLE CARRIER

Daniel Ferris, St. Louis, Mo.

Application February 1, 1946, Serial No. 644,860

2 Claims. (Cl. 224—45)

1

This invention relates to a bottle carrier, and more particularly to such a device for the transportation of bottles of beer, ginger ale, soft drinks, and the like.

A primary object of this invention is the provision of an improved carrier adapted to facilitate the transportation of bottles, whereby a plurality of bottles may be carried substantially as a unit, thus avoiding the difficulty incident to the carrying of a plurality of bottles as individual units.

An additional object of the invention is the provision of such a device which may be readily applied to and removed from the bottles to be carried with a minimum of effort and difficulty.

A further object of the invention is the provision of such a device which will securely hold the bottles in related assembly therewith, obviating the possibility of one or more of the bottles falling from the container, and the consequent chance of breaking thereof.

A still further object of the invention is the provision of such a device which is sturdy and durable in construction, reliable and efficient in operation, and relatively simple and inexpensive to manufacture, assemble and utilize.

Other objects will in part be obvious and in part be pointed out as the description of the invention proceeds, and shown in the accompanying drawings, wherein there are shown preferred embodiments of this inventive concept.

In the drawings:

Figure 1 is a top plan view of one form of carrier embodying features of the instant invention.

Figure 2 is a side elevational view of the device shown in Figure 1, certain portions thereof being broken away and certain concealed parts thereof being indicated in dotted lines.

Figure 3 is a top plan view of the device of Figure 1 shown in a different position of adjustment.

Figure 4 is an end elevational view of the device disclosed in Figures 1 to 3, inclusive.

Figure 5 is a top plan view of a modified form of construction.

Figure 6 is a side view, partially in elevation and partially in section, of the device disclosed in Figure 5.

Similar reference characters refer to similar parts throughout the several views of the drawings.

Having reference now to the drawings, and more particularly to the modification of this invention disclosed in Figures 1 to 4, inclusive, the bottle carrier generally indicated at 10 is comprised of two strips 11 and 12 of substantially

identical length, each provided with a plurality of semicircular apertures 13 and 14, respectively, which, when the strips are aligned in parallel relation, coact to form circular apertures of a diameter slightly greater than the neck of a conventional beer or soft drink bottle, but of less diameter than the bead surmounting the neck of such bottle. The strips 11 and 12 are secured together at one end, as by a metal clip 15, secured 5 to the strip 11, as by rivets or screws 16, and secured to strip 12, as by a pivot pin 17. As best shown in dotted lines in Figure 3, the corner of the strip 12 is cut away, as at 18, to allow limited pivotal movement of the strip 12 with respect to the strip 11. A latch member 20 is secured, as on a pivot 21, to the opposite end of the strip 11 and includes a downwardly depending portion 22, as best shown in Figure 4, and an inturned portion 23 adapted to underlie the strip 12 when in latching position. The portion 23 is bent outwardly and thence downwardly, as at 24, to provide a finger grip by means of which the member 20 may be rotated about the pivot pin 21.

A suitable handle 25 is also provided, preferably 25 comprised of rope or similar flexible material, the opposite ends of which are passed through suitable apertures in the strips 11 and 12 and secured in position, as by knotting the ends as indicated at 26 and 27.

From the foregoing the operation of the device should now be readily understandable. When it is desired to insert bottles into the device, the latch 20 is moved by the finger grip 24 to the position disclosed in Figure 3, and the strips 11 and 12 are separated. The device is then positioned around the neck of the bottles to be carried, and below the bead thereof, whereupon the strips 11 and 12 are moved to the position disclosed in Figure 1, and the latch 20 moved until the portion 23 engages the strip 12, securely holding the strips together. Obviously, after such action the three bottles adapted to be carried may be readily moved as a unit simply by lifting the rope handle 25, the device securely holding the bottles against separation, and correspondingly against damage as by breakage. In the illustrative embodiment above shown, the device is adapted for the carrying of three bottles, but it will be readily understood that this modification 45 may be readily adapted to more or less bottles as occasion may demand.

A modified form of construction is disclosed in Figures 5 and 6. In this form of device there is provided a base plate 30 provided with a plurality of recessed seats 31 of a diameter to accom-

modate the base of a normal beer or soft drink bottle. In the illustrative embodiment shown, the plate 30 is of rectangular configuration and of a dimension to accommodate the bases of six bottles. An upper plate 32 is provided and has a plurality of apertures 33 therein of a number to correspond to the recesses 31, and of a diameter to surround the necks 34 of bottles 35, but not of a sufficient diameter to pass below the necks of such bottles.

The means for securing the two plates 30 and 32 in related assembly about a plurality of bottles take the form of a rope or similar member generally indicated at 36. The rope 36 is provided with a knot 37 above the top plate 32 and passes through a suitable aperture 38 in plate 32 downwardly through an aperture 39 in base plate 30, and thence upwardly through an aperture 40 passing between the plates and outwardly through an aperture 41 in the upper plate 32 forming a handle loop 42. The opposite end of the handle loops 42 passes through an aperture 43 in plate 32 oppositely spaced to the aperture 41, and thence downwardly through an aperture 44 in plate 30 and upwardly through apertures 45 in plate 30 and 46 in plate 32 to terminate in a knot 47.

The loop 42 is of substantial extent in such manner that the plates 32 and 30 may be separated to a distance in excess of the height of a normal beer or soft drink bottle. When it is desired to utilize the device, a plurality of bottles are seated, after the plates have been separated to the full extent permitted by the rope 36, in the depressions 31, and the plate 32 fitted downwardly thereover, the necks 34 of the bottles passing through the apertures 33. Obviously, when the device is picked up by means of the loop 42, due to the arrangement of the parts and the positioning of the rope, the tension exerted by the pull on the handle 42 will cause the two plates 30 and 32 to contract to the limit permitted by the diameter of the apertures 33, thus holding the bottles securely in position within the container.

Now, from the foregoing, it will be seen that there are herein provided improved bottle carriers embodying the features of this inventive concept which accomplish all the objects of this invention, and others, including many advantages of great practical utility and commercial importance.

Since many embodiments may be made of this inventive concept, and since many modifications may be made in the embodiments hereinbefore shown and described, it is to be understood that all matter herein is to be interpreted merely as illustrative and not in a limiting sense.

I claim:

1. In a bottle carrier, a bar having substantially semi-circular recesses in one side, a complementary bar having corresponding recesses, means hinging the bars together at one end, a clip removably holding the bars together at the opposite end, and a flexible handle with one end mounted in the first bar and the other in the complementary bar, the points where the ends of the handle are mounted in the bars being offset wherein the strain on the handle in supporting bottles in the recesses of the bars urges the bars together in clamping relation around the necks of the bottles.
- 10 2. In a bottle carrier, a bar having substantially semi-circular recesses in one side, a complementary bar having corresponding recesses, means hinging the bars together at one end, a clip removably holding the bars together at the opposite end, and a flexible handle with one end mounted in the first bar and the other in the complementary bar, the points where the ends of the handle are mounted in the bars being offset wherein the strain on the handle in supporting bottles in the recesses of the bars urges the bars together in clamping relation around the necks of the bottles.
- 15 3. In a bottle carrier, a bar having substantially semi-circular recesses in one side, a complementary bar having corresponding recesses, means hinging the bars together at one end, a clip removably holding the bars together at the opposite end, and a flexible handle with one end mounted in the first bar and the other in the complementary bar, the points where the ends of the handle are mounted in the bars being offset wherein the strain on the handle in supporting bottles in the recesses of the bars urges the bars together in clamping relation around the necks of the bottles.
- 20 4. In a bottle carrier, a bar having substantially semi-circular recesses in one side, a complementary bar having corresponding recesses, means hinging the bars together at one end, a clip removably holding the bars together at the opposite end, and a flexible handle with one end mounted in the first bar and the other in the complementary bar, the points where the ends of the handle are mounted in the bars being offset wherein the strain on the handle in supporting bottles in the recesses of the bars urges the bars together in clamping relation around the necks of the bottles.
- 25 5. In a bottle carrier, a bar having substantially semi-circular recesses in one side, a complementary bar having corresponding recesses, means hinging the bars together at one end, a clip removably holding the bars together at the opposite end, and a flexible handle with one end mounted in the first bar and the other in the complementary bar, the points where the ends of the handle are mounted in the bars being offset wherein the strain on the handle in supporting bottles in the recesses of the bars urges the bars together in clamping relation around the necks of the bottles.
- 30 6. In a bottle carrier, a bar having substantially semi-circular recesses in one side, a complementary bar having corresponding recesses, means hinging the bars together at one end, a clip removably holding the bars together at the opposite end, and a flexible handle with one end mounted in the first bar and the other in the complementary bar, the points where the ends of the handle are mounted in the bars being offset wherein the strain on the handle in supporting bottles in the recesses of the bars urges the bars together in clamping relation around the necks of the bottles, said recesses forming circular openings of a diameter in excess of that of a neck of a conventional beer bottle but less than that of the bead thereof when said bars are in clamped relation.
